UNITED STATES PATENT OFFICE.

WILLIAM D. YOUNG, OF PITTSBURG, PENNSYLVANIA, ASSIGNOR TO
SHOENBERGER & CO., OF SAME PLACE.

HORSESHOE-MACHINE.

SPECIFICATION forming part of Letters Patent No. 315,206, dated April 7, 1885.

Application filed August 9, 1884. (No model.)

To all whom it may concern:

Be it known that I, WILLIAM D. YOUNG, of Pittsburgh, in the county of Allegheny and State of Pennsylvania, have invented a new 5 and useful Improvement in Horseshoe-Machines; and I do hereby declare the following to be a full, clear, and exact description thereof, reference being had to the accompanying drawings, in which—

10 Figure 1 is a plan view of my improved machine, the parts being in the position occupied when the blanks are fed thereto. Fig. 4 is a similar view of the same when the parts are in position at the end of the bending stroke. 15 Figs. 2 and 3 are vertical longitudinal sections on the line $x-x$ of Fig. 4, showing the parts of the machine in intermediate positions between those shown in Figs. 1 and 4.

Like letters of reference indicate like parts 20 wherever they occur.

Upon suitable bed-plate, k , provided with ways or grooves i , is a traveling carrier, G , which is adapted to slide backward and forward upon said ways or grooves.

25 Pivoted on the carrier g is a pair of bending-jaws, h , each of which has an arm or lever, h' , extending backward toward the rear part of the carrier; and situate back of the carrier G upon the bed-plate k is a sliding cross-head, 30 F , which moves in suitable guides, and is connected with a crank, f , which actuates it and gives it a reciprocating motion. The jaws h are connected separately with the cross-head F by arms or rods e , pivoted to the jaws at 35 points g' outside of the pivotal points e of the jaws, and pivoted to the cross-head at points g'' . The carrier G is slotted longitudinally, as at a' , and projecting upward therethrough to the sides of the arms h' of the jaws h are guide- 40 pins a' , which are preferably of a peculiar construction, which I will now describe. Guide rods or bars a are movably mounted within the slots or grooves a'' in the carrier G , length- 45 wise of the machine, and back of the carrier each bar has an angular downwardly-projecting-arm, a'' , and at its front end is provided with an upwardly-projecting arm, which I have, already denominated the pin a' . The bars a are connected with the carrier G by 50 means of parallel rods c^3 , which pass loosely through holes in the arms a'' , and are screwed

into the body of the carrier G . (See Fig. 2.) Suitable springs, c^2 , adjusted on each of the rods c^3 , between the arms a'' and nuts c' , placed on the ends of the rods c^3 , tend by their pressure to force the bars a toward the carrier G , and the pins a' against the ends of notches h^2 , made at the outer ends of the arms h' . The arms a'' extend below the level of the carrier G to points opposite the bed-plate k , and each 55 arm is provided with an adjustable stop-bar, m , which, as the bar a is carried forward by the carrier G , will strike against the bed-plate somewhat before the crank-arm f has completed its forward stroke. When this happens, 60 the forward motion of the bars a is checked, and the carrier G moves onward without them until the crank-arm f begins its backward stroke, when the springs c^2 , which have in the meantime become compressed, hold the bars 65 a stationary until the pins a' engage the ends of the notches h^2 , and the bars begin to move 70 back with the carrier.

Mounted on the under side of an overhanging support, i' , in front of the carrier G , is a 75 mandrel, i'' , of the shape of the inside of the shoe. It is in the same horizontal plane with the bending-jaws, and its lower side is slightly higher than the upper face of the carrier G , so that the latter may be able to pass under 80 it without binding. Directly below the mandrel a hole is made the bed-plate, through which the bent blanks are discharged after the carrier has been withdrawn.

Ahead of the jaws h on the carrier G , but 85 to one side of the same, is a laterally-adjustable stop o , so situate that a straight horseshoe-blank may be placed on the carrier with one end against the stop and the middle part directly opposite the mandrel i'' . The stop o 90 should be made adjustable, so as to adapt the machine to use in bending blanks of any desired length.

I have already described the arms e as being continuous and pivoted to the cross-head F 95 and to the jaws h . This mode of arrangement is operative and useful; but I prefer to use the modification which I have illustrated in the drawings. The arms e are there represented as being fastened to toggles k' , one arm of each 100 toggle being pivoted to one of the jaws h and the other arm to the sliding head G at g^3 .

The movement of the parts just described is as follows: Starting with the position shown in Fig. 1, the cross-head F advances and pushes the carrier G forward by means of the arms e. 5 During the movement the jaws h are held open by the guide-pins a', which abut against the sides of the jaws in the notches h² until the movement of the carrier G causes the inner corners, h³, of the bending-jaws to encounter 10 the shoe-blank which has been adjusted opposite the mandrel, and forces the ends of the blank inward and around the surface of the mandrel. As this is being done the stop m encounters the end of the bed-plate k, (see 15 Fig. 2,) and the advance of the pins a' stops, while the jaws and carrier continue to move until the jaws are released from the pins, and the blank being now pressed tightly against the mandrel, and into the inner face of the 20 gripping-jaws h, the advance of the carrier G will have been completely checked, (see Fig. 3,) and any further forward motion of the cross-head F will act through the toggle-joints k' upon the jaws h, causing the toggle-joints to straighten and to turn the jaws upon their 25 pivots so that they may close around the mandrel and upon the blank. The crank f will then be at the end of its stroke, and the parts will then be in the relative positions shown in 30 Fig. 4. The power of the crank f increases toward the end of its stroke, and this power is communicated through the cross-head F, arms e, and jaws h to the blank, thus wrapping it strongly around the mandrel and thickening 35 up its ends in an effective and desirable manner. As soon as the sliding head F begins to be retracted with the reverse movement of the crank f, it acts upon the toggles k', opens the jaws h, and pulls them back from the mandrel with 40 the carrier G. During the interval between the striking of the stops m against the bed-plate and the end of the advance of the carrier G the springs c' have been compressed, and as the carrier moves backward these springs 45 hold the guide-bars a stationary until their ends a' engage with the outer sides of the arms h' of the gripping-jaws. The bars a then begin to partake of the motion of the carrier G, as before described. 50 I have said that the forward motion of the carrier G is checked by the jaws coming into contact with the horseshoe-blank, and forcing it against the mandrel i. This is the simplest method of stopping the carrier and of causing 55 the lateral squeezing of the jaws; but for certainty and accuracy of action I prefer to use a device which is shown in the several figures of the drawings. A vertical plate or rod, j, is secured to the outer end of the carrier G 60 and projects downward therefrom. The object of this plate is to hold a stop-bar, b, which extends inward from the plate and at right angles therefrom toward the end of the bed-plate k, or toward the end of a slot made therein. The stop-bar b preferably passes through the plate j, and is secured thereto by a screw-thread, so that its inner extremity may be

adjustable toward or away from the end of the bed-plate. It can thus be set in such manner as to strike the bed-plate at the desired time, and thereby suddenly stop the motion of the carrier G, to which it is attached. (See Fig. 3.) Thus suppose the stroke of the crank-arm f and cross-head F to be twenty-two inches, the stops m should be so adjusted that they will engage the bed-plate k when the sliding head has traveled about nineteen inches, and the stops b are preferably arranged so that they may strike the bed-plate very soon afterward, say, at twenty inches of the stroke. The carrier G then stops, and the remaining two inches of advance of the cross-head F is taken up with the lateral gripping action of the jaws upon the shoe-blank and the thickening up of the ends of the same. 75 80 85 When the above proportion of size of the parts is employed, I prefer to make the notches h³ a little less than an inch in length, so as to release the jaws h just before the stoppage of the carrier G. On the back-stroke of the 90 cross-head F, during the first two inches thereof, the carrier G remains stationary, and the movement of the cross-head merely operates on the toggles to open the jaws h. It then acts on the carrier and retracts it, until, at the 95 end of the next inch, the arms h', which have been closed by the opening of the jaws h, have been locked within the pins a', and the bars a begin to move back with the carrier, as above described. The shape of the mandrel i' prevents the horseshoe-blank from being drawn back with the retraction of the gripping-jaws h; but as soon as the jaws and the carrier G have been moved away from the mandrel the blank may be stripped therefrom through a hole in 100 the bed-plate, or in any other desirable manner. 105

It is obvious that by means of the adjustable stops m and j and the nuts e' at the end of the spring e', the different parts of my apparatus may be adjusted to any size of horseshoe and to operate at any desired intervals of time. 110

The advantages of the machine herein described are its simplicity of construction, its effective operation, and the fact that it thickens the heels of the shoe at the same operation and by the same means used for bending the blanks. It thereby effects a considerable saving of time and labor. 115

I do not desire to limit myself to any particular device for imparting a reciprocating motion to the sliding head F, nor to any particular form for the various parts of the machine; but

What I claim as my invention, and desire to 120 secure by Letters Patent, is—

1. In a machine for bending horseshoe-blanks, the combination of a sliding carrier, a mandrel, bending-jaws pivoted to the carrier, a reciprocating head for actuating the carrier, and connecting mechanism for imparting a lateral movement to the jaws from the reciprocating movement of the head, substantially as and for the purposes specified. 125 130

2. In a machine for bending horseshoe-blanks, the combination of a pair of pivoted bending-dies traveling first in right lines and then having a lateral motion, so as to bend the blank and thicken up the heel of the same, a mandrel, and mechanism, substantially as described, for imparting the double movement to the jaws, substantially as and for the purposes specified. 25
3. In a machine for bending horseshoe-blanks, the combination of the pivoted bending-jaws, devices for imparting a reciprocating movement thereto, guides for causing the jaws to move in a right line, and devices for imparting a lateral movement to the jaws after they have passed the guides, substantially as and for the purposes specified. 30
4. The combination, in a machine for bending horseshoe-blanks, of reciprocating bending-jaws having first a motion in right lines to bend the blank into U form against the mandrel, and then a lateral motion to thicken up the heels of the blank and compress them about the mandrel, with locking-bars a, which hold the jaws open during the rectilinear motion thereof and advance therewith, said locking-bars having suitable stops, which check their motion and release the gripping-jaws at a determined period of their motion, substantially as and for the purposes described. 35
5. The combination of the bending-jaws h, which are pivoted upon a reciprocating carrier, with the locking-bars a, and spring e², adapted to press said bars toward said carrier, substantially as and for the purposes described. 35
6. The combination, with the bending-jaws h h, of the reciprocating carrier G, a suitable stop for checking the advance of said carrier, and devices, substantially as specified, for imparting a lateral movement to the jaws when the carrier comes in contact with the stop, substantially as and for the purposes described. 40

In testimony whereof I have hereunto set my hand this 7th day of August, A. D. 1884.

WILLIAM D. YOUNG.
